United States Patent Office

Des. 205,901
Patented Oct. 4, 1966

205,901

AWARD KEY

Edgar J. Mothershead, Clayton, Mo., assignor to The St. Louis County Medical Society, a corporation of Missouri

Filed May 7, 1965, Ser. No. 85,183

Term of patent 7 years

(Cl. D45—19)

FIG. 2

FIG. 1

FIG. 3

FIG. 4

The back (not shown) is plain and unornamented.

I claim:

The ornamental design for an award key, substantially as shown and described.
